(57) **CLAIM**

We claim the ornamental design for a sampler, as shown and described.

DESCRIPTION

FIG. 1 is a perspective view of a sampler, embodying my new design.

FIG. 2 is a front elevation view thereof.

FIG. 3 is a back elevation view thereof.

FIG. 4 is a right elevation view thereof.

FIG. 5 is a left elevation view thereof.

FIG. 6 is a top plan view thereof.

FIG. 7 is a bottom plan view thereof.

FIG. 8 is a perspective view of the sampler in an alternate configuration of use, showing the sampler tube and sampler wand separately.

FIG. 9 is a front elevation view thereof.

FIG. 10 is a back elevation view thereof.

FIG. 11 is a right elevation view thereof.

(Continued)

FIG. 12 is a left elevation view thereof.
 FIG. 13 is a top plan view thereof; and,
 FIG. 14 is a bottom plan view thereof.
 The broken lines in the drawing views depict portions of the
 design that form no part of the claim.

1 Claim, 8 Drawing Sheets
